TREATMENT OF TEXTILE MATERIALS

Harvey A. Schwartz, Cleveland, Ohio, assignor to
Industrial Rayon Corporation, Cleveland, Ohio,
a corporation of Delaware

No Drawing. Application March 8, 1934,
Serial No. 714,690

11 Claims. (Cl. 8—5)

This invention relates to the treatment of textile materials to alter the dyeing characteristics of the same and, more particularly, to a method of securing cross-dyeing effects by combining materials so treated with others which have not been treated and dyeing the fabric thus formed.

In the manufacture of cross-dyed fabrics, the warp threads may be of one material and the 10 weft threads of another material, the two materials having different dyeing properties when the fabric is dyed. As a result, one set of threads comes out a lighter shade than the other and a cross-dyeing effect is secured. As examples of 15 materials used for this purpose, there may be mentioned cellulose acetate yarn and viscose yarn, the mixed fabric giving a two-color effect due to the fact that the viscose yarn takes the dye more readily than the acetate yarn.

It has now been found that similar cross-dyeing effects may be obtained by the use of only one kind of thread in the fabric. The result may be secured by exposing a quantity of the thread to the effect of radiation containing actinic rays. 20 The thread thus treated, when woven or knitted into a fabric with other untreated thread, will take a dye in a different manner from the untreated thread and produce effects similar to those achieved by the use of two quite different kinds of yarn.

It is, accordingly, an object of the invention to provide a method of treating textile materials to alter the dyeing qualities of the same. Another object of the invention is to provide a method of 25 treating artificial silk thread consisting essentially of regenerated cellulose by means of radiation containing actinic rays to modify its dyeing qualities. A further object of the invention is to provide a method of treating regenerated cellulose thread with radiation containing actinic rays, incorporating this in fabric with untreated thread, and then dyeing the fabric to secure cross-dyeing effects. Other objects of the invention will in part be obvious and will in part appear 30 hereinafter.

The method of the invention may be carried out by subjecting thread, such as viscose, cuprammonium cellulose or nitro-cellulose thread, to the light from a carbon arc lamp, a mercury vapor lamp, or the like. All sides of the thread are exposed to the radiation and the treatment continued as long as necessary to give the desired 35 result. The time of exposure will, of course, vary according to the power of the lamp used and the distance therefrom at which the yarn is located.

The amount of treatment required can be readily determined for any set of operating conditions which may prevail. Preferably, the thread should be exposed in the untwisted condition in order to illuminate a greater thread area and, in 5 practice, the thread may be caused to travel between a plurality of lights which irradiate all sides of it, the rate of travel of the thread through the zone of exposure being so chosen that the desired modification of the dyeing characteristics 10 results.

Thread so treated, when woven or knitted into a fabric and compared with a control fabric made from untreated thread of the same nature, dyes 15 a considerably lighter shade than the control.

The treated thread may be stored for a time until it is desired to work the same up into fabric or the irradiation may be effected and the thread then immediately woven or knitted into fabric and dyed. One practical application of the invention is in the making of cross-dyed fabrics, as mentioned above, in which the warp threads have previously been of one material and the weft threads of another material, the two materials having different dyeing properties. By means of 20 the present invention, it is possible to secure these cross-dyeing effects by the use of one kind of thread, for example, viscose thread. The thread to comprise the warp threads is treated with radiation containing actinic rays, in accordance with 25 the invention, and combined with other untreated thread used as the weft threads. The formed fabric is then dyed and, upon completion of this operation, it is found that the irradiated threads 30 have been dyed a lighter shade than the untreated 35 threads, thus giving a cross-dyeing effect.

The type of radiation may be varied but it is found preferable to include ultra-violet rays therein. The effect is probably superficial, affecting only the surface layer of the individual 40 fibers or filaments but, whether or not the effect is more deep-seated than this, the fact remains that the dyeing characteristics of the treated material are changed. Direct dyes have shown a distinct contrast when applied to a fabric composed of treated and untreated threads, but acid and basis dyes may also be applied where cross-dyeing is desired. 45

It is intended that the patent shall cover, by suitable expression in the appended claims, whatever features of patentable novelty reside in the invention.

What I claim is:

1. A method of securing cross-dyeing effects which comprises subjecting viscose thread to 55

- radiation containing actinic rays, meanwhile controlling the duration and intensity of said radiation so as to effect a modification in the dyeing properties of said thread, weaving or knitting said thread with viscose thread which has not been so treated, and dyeing the fabric so formed.
2. A method of securing cross-dyeing effects which comprises subjecting regenerated cellulose thread to radiation containing ultra-violet rays, meanwhile controlling the duration and intensity of said radiation so as to effect a modification in the dyeing properties of said thread, combining said thread in a fabric with thread which has not been so treated, and dyeing the fabric.
3. A method of securing cross-dyeing effects which comprises subjecting regenerated cellulose thread to radiation containing ultra-violet rays, meanwhile controlling the duration and intensity of said radiation so as to effect a modification in the dyeing properties of said thread, combining said thread in a fabric with regenerated cellulose thread which has not been so treated, and dyeing the fabric.
4. A method of manufacturing dyed regenerated cellulose comprising subjecting the regenerated cellulose to radiation containing actinic rays, meanwhile controlling the intensity and duration of said radiation so as to effect a modification of the dyeing properties of the regenerated cellulose, and, after modification of the dyeing properties of the regenerated cellulose, dyeing the same.
5. A method of manufacturing dyed regenerated cellulose comprising subjecting the regenerated cellulose to radiation containing ultra-violet rays, meanwhile controlling the intensity

and duration of said radiation so as to effect a modification of the dyeing properties of the regenerated cellulose, and, after modification of the dyeing properties of the regenerated cellulose, dyeing the same.

6. A method of manufacturing dyed viscose thread comprising subjecting the viscose thread to radiation containing actinic rays, meanwhile controlling the intensity and duration of said radiation so as to effect a modification of the dyeing properties of the viscose thread, and thereafter dyeing the same.

7. Cross-dyed fabric embodying regenerated cellulose threads the dyeing properties of which have been modified by actinic radiation.

8. Cross-dyed fabric embodying threads of regenerated cellulose the dyeing properties of which have been modified by actinic radiation and other threads the dyeing properties of which have not been modified.

9. Cross-dyed fabric embodying threads of regenerated cellulose the dyeing properties of which have been modified by ultra-violet radiation and similar threads of regenerated cellulose the dyeing properties of which have not been so modified.

10. Cross-dyed fabric embodying viscose threads the dyeing properties of which have been modified by ultra-violet radiation.

11. A cross-dyed fabric comprising threads of normal regenerated cellulose, other threads of similar regenerated cellulose modified by ultra-violet radiation, and a dyestuff in the respective threads added from a single dye bath in varying character and amount according to the extent of modification of said other threads by such ultra-violet radiation.

HARVEY A. SCHWARTZ.
